PRODUCTION OF FUEL OILS FROM
ACID SLUDGE

John H. Cone, Pelly, and Roy V. Comeaux, Baytown, Tex., assignors, by mesne assignments, to Standard Oil Development Company, Elizabeth, N. J., a corporation of Delaware

Application September 18, 1947, Serial No. 774,734

4 Claims. (Cl. 196—148)

1

The present invention is directed to a method of producing fuel oils. More particularly, it is directed to a method for treating acid sludges for recovery of hydrocarbon constituents therefrom which are usable as fuel oils.

In the refining of petroleum, quantities of sulfuric acid are employed to treat naphtha, kerosene, gas oil, and lubricating fractions to produce saleable products. Sulfuric acid treating in the petroleum refinery is largely confined to the treatment of heavy naphthas and lubricating oil fractions. As a result of these treating operations, large quantities of acid sludge accumulate which must be economically processed to recover the valuable sulfuric acid constituents therein and also the enormous quantities of hydrocarbon constituents contained in the acid sludge by chemical reaction or by mechanical entrainment. It is customary practice to hydrolyze acid sludges to recover the sulfuric acid constituents and separate a hydrocarbon phase which may be used as fuel oil. The hydrocarbon phase which is separated from the acid layer in the hydrolysis of acid sludges is quite acidic in nature and contains appreciable quantities of ashy constituents. Before the acid oil may be used as a commercial fuel oil, it is usually necessary to neutralize the acidic constituents by contacting the acid oil with an alkaline solution such as sodium hydroxide. However, this operation is not quite as simple as it appears for the acid oil contains sulfonated bodies which, on reaction with the sodium hydroxide, form salts which are good emulsifying agents. Indeed, the treatment of acid oil with sodium hydroxide is often so difficult that the acid oil or the unhydrolyzed sludge may be burned in the refinery itself as a low grade fuel. This is disadvantageous in that the acidic constituents may attack the burners and the furnaces in which the fuel is consumed, leading to rapid deterioration of this equipment.

Acid sludges obtained from treatment of heavy petroleum fractions for production of lubricating oils are ordinarily hydrolyzed for recovery of a weak sulfuric acid layer and a more viscous hydrocarbon layer. The properties of this hydrocarbon layer may be improved to make it suitable for inclusion into commercial grade fuels by treatment with water under controlled conditions. The normally occurring hydrocarbon layer contains substantial quantities of sulfuric and sulfonic acids that when neutralized with sodium hydroxide solutions in present commercial operations results in a neutralized hydrocarbon fuel of extremely high ash content.

2

Washing the acid fuel with fresh water effects a substantial reduction in ash-forming constituents present in the fuel but the success of this operation is dependent upon close control of hydrogen-ion concentration of the spent wash water. When the pH of the spent wash water is maintained within the range 0.3 to 0.9 good separation of water from oil results and about 75 per cent of the water soluble ash is removed from the fuel. If the pH of the fresh water (spent wash) is decreased below the minimum shown, ash reduction is impaired and when the pH is raised above about 1.0, water-oil emulsions result. It has been found that when wash water containing in solution sodium chloride in amounts in the range from about 1000 to 5000 parts per million of alkali metal chlorides is employed the efficiency of removal of ash forming constituents is not impaired and close control of hydrogen-ion concentration is not imperative. For example, we have successfully washed with salt water, fuels from which the spent wash waters had pH values ranging from 0.3 to 10.6. The overall loss of hydrocarbon in the water layer is decreased by washing with salt water since the lower surface tension water (salt water) tends to decrease mechanical hangup of oil globules in the water layer. The solution of water soluble ash in the water layer is substantially equal for fresh and salt water so long as salt concentration of the salt water is controlled within the limits specified.

It is, therefore, the main object of the present invention to provide a process in which commercial grade fuel oils of low ash content may be produced without the formation of emulsions during the treating operation.

Another object of the present invention is to treat acid oils recovered from acid sludges to remove emulsifiable constituents therefrom.

A still further object of the present invention is to provide a process for recovery of a commercial fuel from an acid solution resulting from the acid treating of petroleum hydrocarbons.

The objects of the present invention may be achieved by hydrolyzing an acid sludge with fresh water to obtain an acid layer and an oil layer, the oil layer being subjected to a washing operation with an alkali metal halide brine following which the brine washed oil is treated with a strong aqueous alkaline solution to neutralize the residual acid constituents therefrom.

Briefly, the present invention may be described as involving the hydrolysis of an acid sludge with fresh water, the separation of an aqueous phase from an oil phase, the washing of the oil phase

with an alkali metal halide brine having a concentration of halide in the range from 1000 to 5000 P. P. M., separating the brine from the washed oil, and neutralizing the washed oil with sodium hydroxide to obtain a finished oil of low ash content and of commercial grade.

In practicing the present invention, an acid sludge resulting from the treatment of petroleum with strong sulfuric acid is hydrolyzed with fresh water. To the mixture undergoing hydrolysis may be added a chemical demulsifying agent, such as for example, a sodium salt of petroleum sulfonic acids. However, the addition of the demulsifying agent is optional and may be dispersed with. It may be mentioned that sodium sulfonates act both as demulsifying and emulsifying agents under particular conditions. The mixture of fresh water and the acid sludge is then heated to a temperature in the range from about 100° to 200° F., following which the mixture is allowed to settle into two phases, an oil phase, and an aqueous phase which will include the hydrolyzed sulfuric acid constituents. The oil phase may have a specific gravity in the range from 0.88 to about 0.92 and will have an acidity corresponding to about 1 to 4 pounds of sodium hydroxide for every barrel of oil layer separated from the acid layer. This acid oil is then washed with about 25 to 100 volume percent of a brine solution, including sodium chloride, in the range from about 1000 to about 5000 P. P. M. of the brine. The washed acid oil layer may then be heated to facilitate the separation and to settle the salt water separated from the oil. The oil may then be conveniently neutralized with an aqueous sodium hydroxide solution and the resulting product may be used as a commercial grade fuel. The sodium hydroxide solution employed in neutralizing the residual acidity of the oil may have a Baumé gravity in the range from about 40° to about 50° Bé, although stronger solutions may be used satisfactorily.

The present invention will be further illustrated by reference to the drawing in which the sole figure presents a preferred mode of carrying out the invention.

Referring now to the drawing, numeral 11 designates a charge line through which an acid sludge, resulting from the treatment with sulfuric acid of a lubricating oil distillate in a propane solution, is charged to the system. It is customary to flux such sludges with a heavy naphtha fraction to reduce the viscosity and to improve the mobility of the sludges for ease of pumping. It will be assumed for purposes of illustration that the acid sludge introduced by line 11 is such a sludge to which has been added a suitable flux. To the acid sludge in line 11 may be added a sufficient amount of water by way of line 12 to cause hydrolysis of the acid in the acid sludge. The mixture of acid sludge and water in line 11 then discharges into a hydrolyzer 13 which is equipped with a heating coil or other heating means 14 to allow the raising of the temperature of the mixture in hydrolyzer 13 to a temperature in the range from about 140° to 200° F. Optionally, the hydrolysis and the heating operation may be conducted by adding open steam by means not shown to the hydrolyzer vessel 13. Hydrolyzer vessel 13 is also provided with a line 15 controlled by valve 16 by way of which a chemical demulsifying agent may be added to assist in the separation between the acid oil layer and acid layer which forms in hydrolyzer 13. There are many chemical de-

mulifying agents on the market and any one of these suitable for use in acid conditions may be employed. This particular step does not form a part of our invention; therefore, further mention of a chemical demulsifying agent will not be made. In any event, the employment of a chemical demulsifying agent is optional since acid sludges usually contain sulfonic acid constituents which are both emulsifying and demulsifying agents, and under most conditions it will be unnecessary to add such a material by way of line 15.

With the adjustment of temperatures and pressures in hydrolyzer vessel 13, a phase separation occurs and an acid oil layer and an acid layer are formed. The acid layer may be discharged from the hydrolyzer vessel 13 by way of line 17 and further treated, concentrated and refortified for reuse in treating petroleum oils. The acid-oil layer is withdrawn from the hydrolyzer vessel 13 by way of line 18 and has admixed with it by way of line 19 a brine of sodium chloride having a concentration in the range between 1000 and 5000 P. P. M. The amount of salt water employed will usually include from about 0.25 volume to 1.0 volume of salt water to every volume of acid oil withdrawn by line 18 from hydrolyzer vessel 13. The admixture of salt water and acid oil flows into an incorporator or other mixing device 20 where intimate admixture between the salt water brine and the acid oil occurs.

Leaving incorporator 20, the admixture flows through line 21 through a heater 22 where the temperature of the admixture is raised to a temperature in the range between 125° F. and 200° F. The heated mixture then discharges by way of line 23 into a settler 24 which is of sufficient capacity to allow a residence time to cause phase separation between the oil layer and the salt water introduced by line 19. The two layers, the oil layer and the salt water layer, in settler 24 are allowed to separate and the salt water is discharged from the system by way of line 25 while the oil layer, withdrawn by line 26, has admixed with it a strong sodium hydroxide solution introduced by line 27, and then discharges into incorporator or similar mixing device 28 where contact with the sodium hydroxide solution occurs to allow neutralization of acidic constituents remaining in the acid oil produced in hydrolyzer 13. The amount of sodium hydroxide employed should be just sufficient to neutralize any residual acidity not removed by the brine wash.

It is not objectionable to employ a highly concentrated solution of sodium hydroxide in a very small amount and let it remain in the oil since the residual acidity after washing the acid oil with sodium chloride brine is of such a small magnitude that the amount of sodium hydroxide necessary to neutralize it will raise the ash content only slightly. After the residual acidity has been neutralized by addition of sodium hydroxide to the oil, it may be routed by line 29 to storage tank 30 where, if desired, it may be blown with air or heated and blown with air by means not shown to remove excess moisture.

In practicing the invention as illustrated in conjunction with the drawing, no emulsification difficulties are encountered and the fuel oil is of satisfactory low ash content.

The invention will be further illustrated by the following examples:

EXAMPLE 1

75 Five hundred barrels of an acid oil obtained

by hydrolysis of an acid sludge resulting from treating a petroleum fraction with strong sulfuric acid had added to it an amount of hot fresh water equivalent to 70 volume percent of the oil. This hot water was intimately admixed with the acid oil in an incorporator and sufficient sodium chloride brine, in an amount to increase the salt content of the wash water to 1500 P. P. M., was added to the mixture. The admixture was transferred into a settling drum and allowed to separate. As soon as 100 barrels of the fuel oil-salt water mixture had been transferred into the settling drum, withdrawal of water was started and continued throughout the remainder of the run. The rate of withdrawal of water was only slightly less than the rate of addition of water to the incoming fuel oil. One hour after the transfer of the oil to the settling drum had been started, all of the wash water had been withdrawn. No emulsion difficulties were encountered and acid removal averaged 70%. The brine washed fuel was then neutralized with a sodium hydroxide solution; the neutralized solution was then blown with air to remove residual moisture. The total elapsed time for the washing and withdrawal of water during this run was two hours and forty-five minutes.

The original fuel washed with the salt water had a gravity of 20° A. P. I. and a neutralization value expressed as pounds of sodium hydroxide per barrel of oil of 1.74. This fuel without washing with salt water had an average total ash content of 1.05% and a water soluble ash content of approximately 1%. The acid oil contained approximately 1.7% of water.

After the salt water wash and after the oil had been neutralized with sodium hydroxide, the gravity of the oil was found to be 21.3° A. P. I. while the neutralization value in pounds of sodium hydroxide per barrel of oil was 0.59.

water increased from 1500 P. P. M. to 1687 and varied thereafter to 1994, 1177, and 1381 P. P. M., with a final chloride content of 1738 P. P. M. at the finish of the run.

- 5 It will be apparent from the foregoing run that the gravity of the salt water washed and caustic neutralized fuel has been appreciably increased over that of the original acid oil. It will be further apparent that the total ash and water soluble ash content has been reduced appreciably by the salt water washing and increased only slightly by reaction of the acid constituents with sodium hydroxide. It is also apparent that the salt water wash removes appreciable amounts of acidic constituents from the acid oil in view of the neutralization values of the withdrawn salt water.

EXAMPLE 2

- 20 A number of runs were made in which acid oil was agitated with both sodium chloride brine and fresh water. The acid oil and the wash water were heated in separate containers at temperatures in the range of 180° to 195° F., the acid oil being agitated with 50-100 volume percent of the washing medium. With fresh water, the acid oil was shaken for one minute to give best removal of acid and separation of emulsion. For salt water, the agitation time was not critical.
- 25 30 After formation of the fuel-water emulsion, the containers were maintained at 180° to 195° F. and water was withdrawn at intervals of 3, 5, 10, and 20 minutes, or until the total wash water was withdrawn. The criterion for satisfactory separation was arbitrarily set at 90% in 10 minutes. After removal of the water, the fuel layer was tested for acidity to phenolphthalein and then neutralized with 52° Bé. aqueous sodium hydroxide solution and tested for per cents ash, water
- 35 40 soluble ash, and water. The results from these runs are given in the following table:

TABLE I

Original Fuel Acidity; NaOH Required, Lbs./Bbl.	Water Wash		Separation Per Cent after Minutes				Wash Water, pH	Washed NaOH Neutralized Fuel		
	Vol. Per Cent	Type	3	5	10	20		Ash Per Cent	WS Ash Per Cent	H ₂ O

1.50	---	Fresh	0.6	1.3	3.3	6.5	---	0.67	0.63	1.8
1.50	75	do	78	90	100	102	1.29	0.26	0.26	0.9
1.50	75	Salt ¹	---	---	---	---	1.28	0.26	0.25	3.0

¹ Water containing 1640 P. P. M. chlorides.

² 100+ per cent theoretical caustic added to original wash water.

The total ash content was 0.34% and the water soluble ash content 0.28%. The water content of the oil was 1.2%.

Analysis of the salt water separated from the oil after the washing operation showed it to have a neutralization value in pounds of sodium hydroxide per barrel ranging from 8.5 at the outset down to 2.13 at the finish of the run with the remainder of the values being intermediate the two. After the first hour, the neutralization value had dropped to 3.75 and declined thereafter to 2.13. The chloride content of the salt

65 It will be apparent from the foregoing data that the salt water allowed separation of more water in a shorter time than the fresh water. It will also be apparent that after the separated oil had been neutralized with sodium hydroxide the ash content of the salt water washed oil was not appreciably greater than that which had been washed with fresh water. Attention is directed to the pH of the wash water when fresh water was employed. It will be noted that when the pH was controlled below about 0.9, separation of water from the acid oil was realized in a

very short period of time. However, when the pH was above about 0.9, the separation was retarded, and when it was about 1, practically negligible separation was realized. On the other hand, the pH of the brine appears to be immaterial since good separation was obtained even when the pH was as high as 10.6 and as low as 0.85.

EXAMPLE 3

In order to illustrate the critical feature of employing a brine of an alkali metal halide in the water washing operation, comparative runs were made in which a portion of acid oil was washed with both a sodium chloride brine and another portion of the same oil was washed with a calcium chloride brine having the same concentration of chlorides. After the respective brines had been separated from the oil, the oil was neutralized with sodium hydroxide and tested. The results of these comparative runs are shown in the following table:

TABLE II
Water washing of acid fuel oil¹

Type of Salt in Wash Water	NaCl	CaCl ₂

pH of Recovered Wash Water	0.75	0.72
Inspections on Washed Fuel:		
Neutralization Value (Mg NaOH/cc. Fuel)	2.149	3.181
Inspections on Neutralized Fuel:		
Total Ash, Percent	0.25	0.41
Water Soluble Ash, Percent	0.24	0.39
Water Content, Percent	2.4	2.3

¹ Acid oil required 2.45 pounds NaOH per barrel of oil to neutralize to the phenolphthalein end point.

² Equivalent to 0.545 pound NaOH/Bbl.

³ Equivalent to 0.645 pound NaOH/Bbl.

It will be apparent from the foregoing data that the calcium chloride brine is ineffective in allowing separation from the acid oil after 20 minutes time, and only after 60 minutes had elapsed did complete separation result with the oil washed with the calcium chloride brine, whereas the separation was complete with the oil washed with sodium chloride brine after twenty minutes. It will thus be seen that, if calcium chloride brine is employed, the settling time will be three times longer than when employing sodium chloride brine as the washing medium. Even though longer settling times were required for the calcium chloride, it will be further apparent that the oil after washing with calcium chloride had a higher neutralization value than the sodium chloride brine washed oil, indicating that more sodium hydroxide would be needed to cause neutralization of the calcium chloride washed oil. Furthermore, the ash contents of the calcium chloride washed oil were appreciably greater than the ash contents of the sodium chloride brine washed oils.

The invention has been illustrated by examples

in which acid oils separated from acid sludges have been washed with sodium chloride brines. While other brines, such as calcium chloride brines, of the group II metals are unsuitable in the practice of the present invention, the corresponding brines of the group I alkali metal halides may be employed in lieu of sodium chloride; for example, brines of potassium chloride and lithium chloride may be employed instead of sodium chloride brines.

The nature and objects of the present invention having been completely described and illustrated, what we wish to claim as new and useful and to secure by Letters Patent is:

1. A method for producing a fuel oil from acid sludge resulting from the treatment of petroleum with sulfuric acid which comprises hydrolyzing an acid sludge at a temperature in the range between 100° and 200° F. to obtain an acid-oil layer and an acid layer, separating the two layers and washing the acid-oil layer with a brine of an alkali metal halide, separating the brine from the acid oil, and neutralizing the oil with a sodium hydroxide solution.
2. A method for producing fuel oil from an acid-oil obtained by hydrolyzing an acid sludge resulting from the treatment of petroleum with sulfuric acid at a temperature in the range between 100° and 200° F. which comprises washing said acid-oil with a brine of an alkali metal halide, separating the brine from the acid oil, and neutralizing the acid oil with a sodium hydroxide solution.
3. A method for producing a fuel oil from an acid-oil resulting from the hydrolysis at a temperature in the range between 100° and 200° F. of an acid sludge obtained by treatment of petroleum with sulfuric acid which comprises washing said acid oil with a sodium chloride brine having a concentration of chloride in the range between 1000 parts per million to 5000 parts per million, separating the brine from the acid-oil and neutralizing the acid oil with a sodium hydroxide solution.
4. A method for producing fuel oil which comprises hydrolyzing an acid sludge, obtained by treatment of a lubricating oil distillate with sulfuric acid, at a temperature in the range between 100° and 200° F. to form an oil layer and an aqueous layer, separating said oil layer from said aqueous layer, washing the oil layer with a sodium chloride brine having a concentration of chloride in the range between 1000 parts and 5000 parts per million, separating the brine from the washed oil, and neutralizing the washed oil with a sodium hydroxide solution.
